UNITED STATES PATENT OFFICE.

WILLIAM J. HERRBOLD, OF KALAMAZOO, MICHIGAN.

PAPER-STOCK-TREATING MACHINE.

1,391,056.

Specification of Letters Patent. Patented Sept. 20, 1921.

Application filed June 19, 1920. Serial No. 390,122.

To all whom it may concern:

Be it known that I, WILLIAM J. HERRBOLD, a citizen of the United States, residing at Kalamazoo, county of Kalamazoo, State of Michigan, have invented certain new and useful Improvements in Paper-Stock-Treating Machines, of which the following is a specification.

This invention relates to improvements in paper stock treating machines.

My improved stock treating machine is especially designed by me for use in treating old paper disintegrating the same for use as paper stock, although it is desirable for use in treating other fibrous material designed for paper stock.

The main objects of this invention are:

First, to provide an improved stock treating machine which effectively disintegrates or separates the fibers without a grinding action or abrading.

Second, to provide an improved stock treating machine which is of very large capacity.

25 Further objects, and objects relating to structural details will definitely appear from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing forming a part of this specification, in which:

Figure I is a vertical longitudinal section of a paper stock treating machine embodying the features of my invention, parts being shown in elevation for convenience in 40 illustration.

Fig. II is an enlarged detail vertical section on a line corresponding to line 2—2 of Fig. IV.

Fig. III is a detail vertical section on a 45 line corresponding to line 3—3 of Figs. II and IV, parts being shown in full lines.

Fig. IV is a detail horizontal section on a line corresponding to line 4—4 of Figs. I, II and III.

50 Fig. V is a detail transverse section through the agitator on a line corresponding to line 5—5 of Fig. I.

In the drawing, similar reference characters refer to similar parts throughout the 55 several views, and the sectional views are

taken looking in the direction of the little arrows at the ends of the section lines.

Referring to the drawing, 1 represents a stock tank, the tank illustrated being such as are commonly employed for rotary boilers in paper mills. This tank is provided with end plates 2 and 2'. The end plate 2' has a bracket 3 thereon mounted on the pedestal 4, the end plate 2 has a bearing 5 thereon for the shaft 6 which projects through into the bearing 7 on the pedestal 8. A supporting pedestal 9 is disposed near the pedestal 8 to engage the under side of the tank.

A steam pipe 10 projects into the tank to heat its contents, the pipe being perforated so that the steam is admitted directly to the tank, the perforations not being illustrated as they will be readily understood.

The end plate 2' carries the bearing 11 for the rear end of the shaft 6 which is driven from the gear 12 on its front end.

The shaft 6 is provided with arms 13 arranged in series to support the agitator bars 14 which are preferably of round cross section as shown, the bars being formed of 80 pieces of pipe.

The brackets 15 are mounted on the ends of the arms and have seats 16 therein to receive the bars, the bars being secured by bolts 17—see Fig. V.

The stock is supplied to the tank through the intake 18. Mounted on the tank near its front end is the chamber 20 having an internal spiral 21.

The top plate 22 for the chamber 20 is loosely mounted so that the material may escape over the upper edge of the chamber. This top plate is held under pressure by means of the spring 23 and the weight 23', the springs being arranged on the guide rods 95 24 carried by the top member 22 and arranged through holes in the top 35 of the housing 30.

The material is discharged into the chamber from the nozzle 25 connected to the discharge pipe 26 of the circulating pump 27. The top member 22 is provided with a down-turned flange 28 at its outer edge so that the material is directed therefrom downwardly against the concave deflector member 29 105 mounted on the outer side of the chamber 20. The housing 30 is mounted on the top of the tank above the opening 31 so that the material is discharged back into the tank and circulates therethrough to the intake 32 110

of the pump. This pipe has a discharge or draw-off connection 33 controlled by the three-way valve 34.

With this arrangement of parts, the stock or material discharged from the nozzle 25 is whirled and agitated by the spiral within the disintegrating chamber and is discharged from the top thereof under the top or pressure plate which is sufficiently weighted so that the desired pressure is maintained within the chambers. The material is discharged from the chamber onto the deflector member 29 and from thence into the tank in which it is circulated as described. The disintegrating 15 of the stock is very effective and rapid and is without grinding or abrading action.

I have illustrated and described my improvements as adapted for use of a rotary boiler now quite generally used in paper mills as a stock tank. However, the tank 20 may be greatly varied in shape and size as occasion requires.

I have not attempted to illustrate and describe various modifications and adaptations 25 which I contemplate as I believe the disclosure made will enable those skilled in the art to which my invention relates to embody or adapt the same as may be desired.

Having thus described my invention, what 30 I claim as new and desire to secure by Letters Patent, is:

1. In a stock treating machine, the combination of a tank, a chamber provided with an internal spiral, a top plate for said chamber 35 movably mounted to permit the escape of material from the top of the chamber, said top member having a downturned flange at its outer edge, a pressure means for said top plate, a concave deflector member mounted 40 on the outer side of said chamber below said top plate, a nozzle disposed to deliver upwardly within said chamber, a housing embracing said chamber and open at its lower end to discharge into said tank, and a pump 45 having a discharge connection to said nozzle and an intake connection to the bottom of said tank.

2. In a stock treating machine, the combination of a tank, a chamber provided with 50 an internal spiral, a top plate for said chamber movably mounted to permit the escape of material from the top of the chamber, a pressure means for said top plate, a nozzle disposed to deliver upwardly within said 55 chamber, a housing embracing said chamber and open at its lower end to discharge into said tank, and a pump having a discharge connection to said nozzle and an intake connection to the bottom of said tank.

60 3. In a stock treating machine, the combination of a tank, a chamber, a top plate for said chamber arranged to permit the escape of material from the top thereof, said top plate having a downturned flange at its 65 outer edge, a concave deflector member on

the outer side of said chamber below said top plate, a nozzle disposed to deliver upwardly within said chamber, a housing embracing said chamber and open at its lower end to discharge into said tank, and a pump 70 having a discharge connection to said nozzle and an intake connection to the bottom of said tank.

4. In a stock treating machine, the combination of a tank, a chamber, a top plate for 75 said chamber arranged to permit the escape of material from the top thereof, said top plate having a downturned flange at its outer edge, a deflector member on the outer side of said chamber below said top plate, a 80 nozzle disposed to deliver upwardly within said chamber, a housing embracing said chamber and open at its lower end to discharge into said tank, and a pump having a discharge connection to said nozzle and an 85 intake connection to the bottom of said tank.

5. In a stock treating machine, the combination of a tank, a chamber provided with an internal spiral, a top plate disposed to permit the escape of material from the top 90 of the chamber, a pressure means for said top plate, a deflector member on the outside of said chamber and against which the material is directed from said top plate, a nozzle disposed to deliver upwardly within said 95 chamber, a chamber housing embracing said chamber and open to discharge into said tank, and a pump having a discharge connection to said nozzle and an intake connection to the bottom of the tank. 100

6. In a stock treating machine, the combination of a tank, a chamber provided with an internal spiral, a top plate disposed to permit the escape of material from the top of the chamber, a deflector member on the outer 105 side of said chamber and against which the material is directed from said top plate, a nozzle disposed to deliver upwardly within said chamber, a chamber housing embracing said chamber and open to discharge into said 110 tank, and a pump having a discharge connection to said nozzle and an intake connection to the bottom of the tank. 110

7. In a stock treating machine, the combination of a tank, a chamber, a top plate 115 disposed to permit the escape of material from the top of the chamber, a pressure means for said top plate, a deflector member on the outer side of said chamber and against which the material is directed from the top 120 plate, a nozzle delivering upwardly within said chamber, a housing embracing said chamber and open to discharge into said tank, and a pump having a discharge connection to said nozzle and an intake connection to the bottom of the tank. 125

8. In a stock treating machine, the combination of a tank, a chamber, a top plate disposed to permit the escape of material from the top of the chamber, a deflector 130

mounted on the outer side of said chamber and against which the material is directed from the top plate, a nozzle delivering upwardly within said chamber, a housing embracing said chamber and open to discharge into said tank, and a pump having a discharge connection to said nozzle and an intake connection to the bottom of the tank.

9. In a stock treating machine, the combination of a tank, a chamber provided with an internal spiral, a top plate disposed to permit the escape of material from the top of the chamber, an upwardly flaring nozzle disposed to deliver upwardly within said chamber, a housing embracing said chamber and open to discharge into said tank, and a pump having a discharge connection to said nozzle and an intake connection to the bottom of the tank.

10 10. In a stock treating machine, the combination of a tank, a chamber, a top plate disposed to permit the escape of material from the top of the chamber, a pressure means for said top plate, a nozzle delivering upwardly within said chamber, a housing embracing said chamber and open to dis-

charge into said tank, and a pump having a discharge connection to said nozzle and an intake connection to the bottom of the tank.

11. In a stock treating machine, the combination of a cylindrical horizontally disposed tank, an agitator comprising a shaft provided with arms and bars of cylindrical cross section mounted on said arms, a chamber mounted on the top of said tank, a top plate for said chamber arranged to permit the escape of material treated from the top of the chamber, a nozzle disposed to deliver upwardly within said chamber, a housing embracing said chamber and open at its lower end to discharge into said tank, and a pump having a discharge connection to said nozzle and an intake connection to the bottom of said tank.

In witness whereof I have hereunto set my hand and seal in the presence of two witnesses.
